UNITED STATES PATENT OFFICE

ROBERT F. GOLDEN, OF SOUTH ORANGE, NEW JERSEY, ASSIGNOR TO THE NATIONAL LOCK WASHER COMPANY, OF NEWARK, NEW JERSEY, A CORPORATION OF NEW JERSEY

SPUT

Application filed July 11, 1928. Serial No. 291,853.

This invention relates to a novel and improved form of sput, and will be best understood from the following description and the accompanying drawings, in which I have shown selected embodiments of my invention, and in which:

Fig. 1 is a vertical section through a sput and a portion of the sheet to which it is connected.

10 Fig. 2 is a top view of the sput shown in Fig. 1, detached from the sheet.

Fig. 3 is a view corresponding to Fig. 1, but showing another form in which my invention may be embodied.

15 Fig. 4 is a plan view of the device shown in Fig. 3.

Referring first to Figs. 1 and 2, these views show a sput 1 having a hole 2 therein for the reception of a plug, which may be screw-threaded to engage corresponding threads 20 in the hole. The sput is adapted to be connected to a sheet 3, which is preferably provided with an opening having its edge portion bent or folded back away from the opening, with the outer layer 4 spaced from the inner layer 5, so as to leave a space 6 therebetween. This folded-back portion is preferably raised above the plane of the sheet, as shown.

25 The outer surface of the sput preferably has an upper conical portion 7 contacting with the inner surface of the inner layer of the folded-back edge portion, and in this outer surface, preferably along the edge of the sput beneath the conical portion, are a plurality of recesses 8 into which the edge portion of the sheet is forced. The sput above the conical portion may be provided with a shoulder 9.

30 In Figs. 3 and 4, the sput and sheet are connected together in the same manner as in Figs. 1 and 2, except that a ring 10 of sheet material is placed between the sput and the adjacent layer of the sheet. This ring may be used as a gasket, and it also forms means for sealing the plug 11 to the sput. The head of the plug bears on the portion of the ring which is bent horizontally away from the sput hole, as indicated at 12, and at one place 35 this portion 12 may be extended to form an

ear 13 having a hole therein registering with a hole in an ear 14 on the plug. A wire 15 or other sealing means may be passed through these holes. The above arrangement provides means to seal the plug to the ring and consequently to the sput.

In both embodiments shown the sput is securely locked against rotation with respect to the sheet to which it is secured, and this locking is secured in a simple and efficient 60 manner.

I claim:

1. In combination, a sheet having an opening therein with its edge portion bent back away from the opening, and a sput for said opening having a hole for the reception of a plug and an outer surface bearing on said bent-back edge portion, said outer surface having recesses therein into which said edge portion of the sheet is depressed.

2. In combination, a sput having a hole for the reception of a plug and an outer bearing surface, a sheet having an opening to receive the sput, the edge portion of the sheet adjacent the opening being folded back with the layers of the fold spaced from each other and the inner layer bearing on said bearing surface on the sput, and means securing the sheet and sput together and preventing relative movement therebetween.

3. In combination, a sput having a hole for the reception of a plug and an outer bearing surface with recesses therein, and a sheet having an opening to receive the sput, the edge portion of the sheet adjacent the opening being bent back and bearing on said surface and forced into said recesses.

4. A sput having a hole for the reception of a plug and having the outer surface formed with an upper conical portion to bear on the sheet of a drum, the edge of the sput beneath said portion having recesses within which said sheet may be forced.

5. In combination, a sput having a hole for the reception of a plug and an outer bearing surface, a sheet having an opening to receive the sput, the edge portion of the sheet adjacent the opening being folded back with the layers of the fold spaced from each other and the inner layer bearing on said bearing

surface on the sput and the outer layer forming a seat for the head of the plug, and means securing the sheet and sput together and preventing relative movement therebetween.

- 5 6. In combination, a sput having a hole for the reception of a plug, a sheet having a surface lying adjacent a surface of the sput, a ring disposed between said surfaces and having a part thereof forming a bearing for the
10 head of a plug in said hole, and means securing the parts together.

ROBERT F. GOLDEN.
